United States Patent Office

Des. 182,829
Patented May 20, 1958

182,829

COFFEE SERVER

Michael S. Lax, New York, N. Y., assignor to Kromex
Corporation, Cleveland, Ohio, a corporation of Ohio

Application September 30, 1957, Serial No. 48,351

Term of patent 14 years

(Cl. D44—26)

Fig. 1.

I claim:

The ornamental design for a coffee server, substantially as shown.
